UNITED STATES PATENT OFFICE.

GEORGE C. DOBBS AND MALCOLM McGREGOR, OF NEW YORK, N. Y.

APPARATUS FOR SUCCESSIVE TREATMENT OF MOTION-PICTURE FILMS.

1,109,208.

Specification of Letters Patent.

Patented Sept. 1, 1914.

Application filed March 25, 1914. Serial No. 827,217.

To all whom it may concern:

Be it known that we, GEORGE C. DOBBS and MALCOLM McGREGOR, citizens of the United States of America, residing at New York, in the county of New York and State of New York, have invented certain new and useful Improvements in Apparatus for Successive Treatment of Motion-Picture Films, of which the following is a specification.

10 The object of the present invention is to provide an apparatus whereby a continuous strip of motion picture film will be successively treated or exposed to various processes, *i. e.* developed, fixed, washed, etc., during a single operation of the apparatus, thereby simplifying the processes, dispensing with a number of attendants hitherto required for carrying out each process separately, and also saving much time.

20 To accomplish our object, we provide a number of basins or receptacles each to contain the requisite means for treatment and a continuous guide extending through all receptacles and provided with suitable film feeding mechanism, whereby the continuous film is conveyed through the different receptacles to be treated in the latter successively, while passing therethrough.

Our invention also consists in the combination, construction and arrangement of parts, as will be hereinafter more fully set forth in the specification and in the annexed claims.

In the accompanying drawings similar reference characters denote corresponding parts and Figure 1 shows a vertical longitudinal section through the apparatus with some parts broken away; Fig. 2 is a top plan view thereof; Fig. 3 is an enlarged horizontal section through one end of the apparatus; Fig. 4 is a similar section through the opposite end of the apparatus; Fig. 5 is an enlarged perspective view of a part of the film guide or track with a broken away portion in the last compartment; Fig. 6 is a similar view of the guide or track in one of the other compartments; Fig. 7 is a view of a modified detail and Fig. 8 is a cross section on line 8—8 of Fig. 3.

50 Referring more specifically to the drawings *a* denotes a table or stationary frame on top of which our apparatus is mounted. The latter comprises a receptacle *b* divided into a number of water or liquid tight compartments or composed of a number of sections suitably united with one another. In

practice there may be about eight of such compartments or sections of which the first may be used for developing; the second for the hypo or fixing bath; the third may contain a second hypo bath; the fourth and fifth compartments may be used for washing the film; the sixth may contain an alcohol bath; the seventh and the eighth compartments may be used for any other treatment that may be required. As usual, in the drying compartment, there may be a box holding ice with a blower or ventilator therein. In the eighth compartment, polishing pads may be provided for polishing the film.

The film strip *f* to be treated in different compartments is, as usual, perforated and wound upon a roller *c* suitably supported upon the table or frame. This film is adapted to be fed or conveyed successively through the different compartments and to be finally wound up at the opposite end of the table or frame upon a roller *c'* supported on the latter. For guiding the film through the different compartments and from one roller to the other, we provide a continuous track or guide *d* which may be of aluminum or any other suitable material that will be acid proof. This guide is adapted to extend through all the compartments and consists of coiled parts *d'*, one for each compartment. Each coiled part, which is made in form of a radiator pipe, extends throughout the entire width of the compartment and is so arranged therein that it will lie below the level of the liquid contained therein. The end portions *d²*, *d³* of each coil of the track rise to points located above the level and pass through openings *b'* made in the walls of the compartments. The track or guide may be of any suitable construction, but in the present example we have shown the same to be of U-shaped cross section, so that the film conveyed therethrough with its emulsion side on top, will have said side fully exposed to the solution contained in the receptacle. In the last compartment, however, the track is inverted, that is to say, the open side of the U-shaped track will be at the bottom instead of on top as in the preceding compartments, so as to cover the emulsion side and to expose the plain side thereof in order that the latter may be treated by polishing disks (not shown).

For the feeding of the perforated film strip from one roller to the other and through the continuous coiled track or guide,

we provide toothed rollers or drums *e* extending through the coils at the rounded ends thereof, which drums are adapted to engage the perforations of the strip of film, and while revolving to feed the latter. Instead of a separate roller for each winding, there may be one roller *e'* extending throughout the entire width of a compartment and provided with sets of teeth *e''* for each winding (see Fig. 7). The individual rollers *e* or rollers *e'* are fixed to spindles *f* suitably borne in the side walls of the receptacle and extending outwardly at one end. The rollers *e*, *e'* or spindles *f* may be driven by any suitable means. In the present example we have shown a motor *g* supported by the table or frame and a multiple worm spindle *h* extending alongside the receptacle and suitably journaled in bearings *i*. Each spindle of the feeding rollers carries a worm wheel which meshes with the corresponding threaded part of the worm spindle. Transmission of motion from the motor to the worm spindle *h* may be accomplished as shown, by pulley or belt or in any other manner. The external parts *d⁴*, *d⁵* of the track or guide extending toward the rollers *e*, *e'* may be widened at their ends *d⁶* to permit of the film strip being easily and quickly entered into the guide. The starting movement may be imparted to the film strip by means of a toothed roller *k* projecting into the guide or track through a notch *d⁷* and driven from a worm spindle *j* which in its turn is driven through suitable transmission gears from the motor *g*. The apparatus will be so arranged that the first three compartments may have dark room facilities.

Since various modifications in the construction and arrangement of the apparatus may be made by those skilled in the art without departing from the spirit of our invention, we do not limit ourselves to the details shown and described.

What we claim and desire to secure by Letters Patent is:

1. An apparatus for successively treating motion picture films, comprising a plurality of compartments, one for each treatment and a stationary film guide or track extending continuously through all said compartments.
2. An apparatus for successively treating motion picture films, comprising a plurality of compartments, one for each treatment, a stationary film guide or track extending continuously through all said compartments, and means to feed the film in a continuous manner and successively along said guide through the different compartments.
3. In an apparatus for successively treating motion picture films, a stationary coiled guide or track for the said film strip.
4. In an apparatus for successively treat-

ing motion picture films, a number of compartments, one for each treatment, a stationary guide or track for the film strip continuously extending through all the said compartments and having coiled parts, one 70 for each compartment.

5. In an apparatus for successively treating motion picture films, a stationary coiled guide or track of U-shaped cross section.

6. In an apparatus for successively treating motion picture films, a number of compartments, a stationary coiled guide or track for the film strip continuously extending through all the said compartments and being of U-shaped cross section.

7. In an apparatus for successively treating motion picture films, a number of compartments, a stationary guide or track for the film strip continuously extending through all the said compartments and 85 means for feeding the film through said guide.

8. In an apparatus for successively treating motion picture films, a number of compartments, a stationary guide for the film 90 strip continuously extending through all the said compartments, and feeding means in said guide for conveying the film continuously therethrough.

9. In an apparatus for successively treating motion picture films, a receptacle, a stationary film guide therein and driven toothed rollers to engage and feed the film continuously through said guide.

10. In an apparatus for successively treating motion picture films, a coiled film guide or track each winding of which has rounded ends, and driven toothed rollers arranged at the said rounded ends of said guide or track to engage and feed the film continuously 105 through said guide.

11. In an apparatus for successively treating motion picture films, a stationary coiled film guide or track, film feeding mechanisms therein and a driven spindle for 110 driving said feeding mechanisms.

12. In an apparatus for successively treating motion picture films, a plurality of liquid receptacles, a continuous stationary film guide or track extending through all 115 said receptacles, a film feeding mechanism in each receptacle and means for transmitting motion to said feeding mechanisms.

13. In an apparatus for successively treating motion picture films, a liquid receptacle divided into water tight compartments, a stationary film guide or track composed of coils one for each compartment and connected to one another to form a continuous guide or track, film feeding mechanism in 125 each compartment and driving means for said feeding mechanism.

14. In an apparatus for successively treating motion picture films, a liquid receptacle divided into water tight compartments, a 130

film guide composed of coils one for each compartment and connected to one another to form a continuous guide or track, film feeding mechanism in each compartment 5 and a driven spindle extending alongside said receptacle and transmitting motion to said feeding mechanisms.

15. In an apparatus for successively treating motion picture films, a liquid receptacle 10 divided into water tight compartments, a film guide composed of coils one for each compartment and connected to one another to form a continuous guide or track, film feeding mechanism in each compartment 15 and a driven multiple worm spindle extending alongside said receptacle and transmitting motion to said mechanisms.

16. In an apparatus for successively treating motion picture films, a coiled film guide 20 of U-shaped cross section, the coil at one end

being arranged inverted with respect to the other coils.

17. In an apparatus for the successive treatment of a continuous motion picture film, a receptacle divided in a plurality 25 of water tight compartments, a guide or track for the film strip extending continuously through all compartments and composed of coiled sections, each coil being adapted to be submerged in the liquid and 30 its end parts rise above the level thereof, and film feeding means in each compartment.

In testimony whereof we affix our signatures in presence of two witnesses.

GEORGE C. DOBBS.

MALCOLM McGREGOR.
